CLAIM

We claim the ornamental design for an absorbent shield for penis leakage, as shown and described.

DESCRIPTION

FIG. 1 is a perspective view of an absorbent shield for penis leakage showing our design in a position of use on a penis.

FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof; and,

FIG. 7 is a right side elevation view thereof.

The broken lines shown in FIG. 1 illustrate environment and form no part of the claimed design.
